LLP

(51) **LOC (9) Cl.** **10-04**

CLAIM

(52) **U.S. Cl.** **D10/78**

The ornamental design for a wall scanner with pistol-grip handle, as shown and described.

(58) **Field of Classification Search** D10/78;
33/286, 290; 324/67, 156, 228, 326, 508,
324/662, 671

DESCRIPTION

See application file for complete search history.

(56) **References Cited**

FIG. 1 is a rear perspective view of a wall scanner with pistol-grip handle of the present invention.

U.S. PATENT DOCUMENTS

FIG. 2 is a front view of the wall scanner of FIG. 1.

FIG. 3 is a right side view of the wall scanner of FIG. 1.

FIG. 4 is a left side view of the wall scanner of FIG. 1.

FIG. 5 is a rear view of the wall scanner of FIG. 1.

FIG. 6 is a top view of the wall scanner of FIG. 1; and,

FIG. 7 is a bottom view of the wall scanner of FIG. 1.

The ornamental design which is claimed is shown in solid lines in the drawings. The portions of the design shown in broken lines are included for the purpose of illustrating environment and form no part of the claimed design. The portions of the design shown in broken lines having unequal segments illustrate the boundary of the claimed design and form no part of the claimed design.
